UNITED STATES PATENT OFFICE.

MUSCOE L. SPOTSWOOD AND TURNER A. WELLER, OF RICHMOND,
VIRGINIA.

TOBACCO-PIPE.

No. 821,836.

Specification of Letters Patent.

Patented May 29, 1906.

Application filed March 10, 1904. Serial No. 197,437.

To all whom it may concern:

Be it known that we, MUSCOE L. SPOTSWOOD and TURNER A. WELLER, citizens of the United States, residing at Richmond, in the county of Henrico and State of Virginia, have invented certain new and useful Improvements in Tobacco-Pipes, of which the following is a specification.

The purpose of this invention is to provide an attachment for general use in connection with tobacco-pipes to prevent the clogging of the opening through the stem, to obviate the use of a penknife or other instrument for cleaning the bowl after smoking, to enable the tobacco to be packed tightly within the bowl without impairing the draft, thereby insuring a long smoke and at the same time obviating rapid consumption of the tobacco, and, lastly, to provide for removal of the ashes and residue and to dissipate any saliva that may tend to collect in the bottom of the bowl whereby the disagreeable noise incident to sucking when smoking is wholly obviated.

The invention consists of a perforated plate or diaphragm adapted to form a false bottom within the bowl and a clip springing from or connected with said plate or false bottom and located at one side thereof, said clip being preferably an integral part of the plate or diaphragm and having its outer member constructed to make positive engagement with the outer side of the bowl, so as to prevent casual displacement of the attachment when the pipe is inverted and the bowl tapped so as to dislodge any ashes that may be contained therein.

The invention will be more particularly set forth hereinafter and claimed and is illustrated in the accompanying drawings, in which—

Figure 1 is a perspective view of a tobacco-pipe provided with an attachment constructed in accordance with this invention. Fig. 2 is a side view of the pipe, the bowl and false bottom or diaphragm being in section. Fig. 3 is a perspective view of the attachment.

Corresponding and like parts are referred to in the following description and indicated in all the views of the drawings by the same reference characters.

The tobacco-pipe is of the type most generally used and comprises the bowl 1, stem 2, and mouthpiece 3. The bowl may be of briar-root or other material commonly em-

ployed in the manufacture of tobacco-pipes. 55 The outer side of the bowl is enlarged or swelled intermediate of its ends, as shown at 4, and this swell is utilized as a means for positively holding the attachment in place.

The attachment consists, essentially, of the 60 plate or diaphragm 5, which is perforated and of a diameter to snugly fit within the lower portion of the bowl, so as to leave a chamber beneath said plate to insure ample draft, notwithstanding the tobacco may be 65 closely packed. A spring-clip 6 is located at one side of the plate or diaphragm 5 and is preferably an integral part thereof, although it may be connected thereto in any manner, so as to form, in effect, a part thereof. The 70 inner member 7 of the clip conforms to an element of the inner wall of the bowl, so as to fit close thereagainst. In the pipe shown the inner walls of the bowl are straight. Hence the member 7 of the clip conforms to 75 the profile of the bowl before the outer member 8 of the clip is outwardly deflected at a point between its extremities, so as to conform to the bulge or swell 4 of the bowl. The entrance to the clip is contracted, and the 80 peculiar formation of the member 8 of the clip enables the lower portion 9 of the member 8 to bear against the lower portion of the bowl with sufficient pressure to retain the attachment in place even if the pipe is inverted 85 and the bowl smartly tapped. The lower end of the member 8 is coiled to form a finger-piece 10, by means of which the attachment is readily manipulated.

The plate 5 and members 7 and 8 of the 90 clip are flat, thereby enabling the device to be constructed of sheet metal and to occupy a minimum amount of space when fitted to a pipe. The outer member of the clip fits close against the outer side of the bowl 95 throughout its length and is composed of oppositely-inclined parts so shaped as to bear against the outer side of the bowl and retain the plate 5 in proper position against any possible displacement when the pipe is inverted or tilted. Moreover, the outer member 100 is longer than the inner member 7, so as to extend well down upon the base of the bowl and insure convenient position of the finger-piece 10.

When the attachment is applied to a pipe, the clip 6 embraces and grips the side portion of the bowl so as to retain the article in

position, and when it is required to clean the bowl ashes and other residue are removed with the false bottom simultaneously with the withdrawal of the attachment from the bowl. When the attachment is removed and it is found that it contains unconsumed tobacco, the latter may be replaced by means of the attachment and the smoke continued, thereby obviating the necessity for relighting or the derangement of the tobacco. During the smoking operation the plate or false bottom 5 becomes heated, and any saliva that may find its way into the bottom of the bowl is converted into vapor by the heat of the plate 5 and it is dissipated, thereby preventing the accumulation of any saliva, which is the source of the disagreeable noise incident to the smoking of tobacco-pipes, especially when the smoke is protracted and the pipe held in the mouth for a great length of time. As is well known, it is common for a smoker after finishing his smoke to empty the contents of the bowl of the pipe by knocking said bowl against an object at hand. The formation of the spring-clip 6 is thus possessed of further advantage in that it positively engages the bowl, so that should the same be jarred, particularly in emptying the ashes from the bowl in the manner just above described, there is no likelihood of displacement of the clip, which might cause inconvenience and trouble on the part of the smoker. While the ashes are preferably re-

moved by lifting the plate 5 of the attachment, yet it will be readily seen that the greater bulk of the ashes may be displaced merely by inversion of the bowl, as above set forth, and when the ashes are removed in this way preparatory to withdrawal of the plate 5 it is important that the attachment should be firmly held in place by the clip.

Having thus described the invention, what is claimed as new is—

1. A tobacco-pipe attachment consisting of a perforated plate and a spring-clip formed from a sheet metal, the inner clip member being flat and the outer member having oppositely-inclined portions as and for the purpose described. 45

2. A new article of manufacture; a tobacco-pipe attachment, the same comprising a perforated plate and a spring-clip formed of a sheet-metal blank, the clip members being flat and adapted to lie close against the inner and outer walls of the pipe-bowl, the outer member being longer than the inner member and composed of oppositely-inclined parts, substantially as specified. 50

In testimony whereof we affix our signatures in presence of two witnesses:
